UNITED STATES PATENT OFFICE.

CHARLES G. MORTIMER, OF GLEN RIDGE, NEW JERSEY.

TAPE-FEEDING MACHINE.

Application filed March 27, 1924. Serial No. 702,421.

To all whom it may concern:

Be it known that I, CHARLES G. MORTIMER, a citizen of the United States, and a resident of Glen Ridge, county of Essex, and 5 State of New Jersey, have invented certain new and useful Improvements in Tape-Feeding Machines, of which the following is a specification.

This invention relates to an improved 10 tape feeding and moistening device which operates so that gummed tape usually made of stiff paper and which is used for sealing packages and parcels is projected from the machine and cut off at the desired 15 length.

The particular machine embodied in this invention is one that is easily operated and has also the advantage of maintaining its 20 parts in alignment and in proper working order throughout long and continuous operation, the structure being such that the parts are compactly arranged and in which gears and a rack for actuating the feeding and moistening rolls are constantly in mesh.

25 The invention is also designed to provide a machine of this kind in which there can be a quick and convenient adjustment to provide for either short or long lengths of tape delivered during one operation of the 30 handle.

The invention is illustrated in the accompanying drawings in which Figure 1 is a vertical section taken on line 1—1 in Figure 3. Figure 2 is a side view of the machine. Figure 3 is a front view of the machine with the cover shown in section and with the front plate of the tank removed. Figure 4 is a side view of the front part of the machine, this view being similar to 40 Figure 2 except that the shield carrying the adjusting mechanism is removed. Figure 5 is a view of the other side of the machine with the shield on that side partly broken away. Figure 6 is a section taken on line 45 6—6 in Figure 1. Figure 7 is a section taken on line 7—7 in Figure 2. Figure 8 is a sectional detail of one of the clutches in the machine.

50 The machine consists of a frame which is provided at the back with a well or other suitable means for holding the roll of tape 10. The frame is usually made of side pieces 11 between which is supported the bottom 12 of the well 13 although other 55 means of securing the roll 10 of tape can be used.

At the front end of the machine I arrange the feeding and moistening mechanisms, the feeding mechanism consisting of the feed roll 14 and the feed roll 15 above it these being pressed together by the spring 16 in each side bearing 17 of the roll 15. These rolls operate in unison by reason of the meshed gears 18 and 19 connecting the 60 shafts of the rolls, the roll 14 being secured to the shaft 20 which projects at one side of the machine and is operated from a gear 21, and a suitable clutch mechanism which is shown in detail in Figure 8.

The gear 21 is in the nature of a hub on 65 the shell 22 which surrounds the arms 23 secured on the end of the shaft 20. The face 24 of each arm is tangential to the centre of the shaft and the rollers 25 are thus caused to bind when the shell 22 is rotated 70 in one direction and thus carries the shaft 20 with it but when moved in the opposite direction the rollers retreat and there is no transmission of movement from the gear to 75 the shaft.

In front of the feed rollers and spaced 80 therefrom are moistening rollers one of which is the roller 26 which does the actual moistening since it rotates with part of its 85 surface in water in the tank 27. The other roller 28 simply presses by its own weight on the roller 26, since its bearings ride freely in the slots 29 in the upper part of the side plates 11 of the frame.

The roller 26 is mounted on the shaft 30 90 which is equipped with a gear 31 on the shell 32 similar to the shell 22 of the feeding roll 14 so that the moistening roll also 95 operates with the gear only in one direction and is released therefrom when moved in the other direction. The gears 21 and 31 are in mesh with the rack 34 which includes a plate 33 having the pivotal bolt 35 which passes through the frame of the machine and is fastened by such means as a cotter pin 36 on the opposite side.

The rack 34 is arc-shaped and being arcuate with the bolt 35 as a centre. The gears 105 21 and 31 are disposed so that they are in the path of travel of the rack 34 and are always in mesh with it. The rack is yieldingly held in normal position by a spring 37 and is stopped on its backward movement by the stop 38 which is usually covered with 110 rubber so as to deaden the noise.

The rack has a handle 39 which when pushed down swings the rack on its centre

and operates the feed rolls and the moistening rolls to project tape from the roll 10. To govern the amount of tape to be supplied at any particular time I provide a quick adjustment for limiting forward movement of the rack. This stop consists of a shield 40 which also acts as a cover for the curved rack and its associated parts and it has a swinging plate 41 underneath which swings 10 across an opening or slot 42, one edge of which has the teeth 43.

The latch 44 is adapted to engage any one of these teeth, being mounted on the pivot 45 and having the spring 46 to press it normally in engagement with the teeth 43. On the inner face of this plate which forms really part of the wall of the shield, is the stop 47 so that as the latch 44 which projects through the slot 42 and forms a finger piece, is adjusted it carries with it of course, the stud 47 which is in the path of the stud 48 (see Figure 4) which when it is brought forward by the operation of the handle 39 engages the stop 47. Therefore it will be 25 evident that if the rack 34 is only permitted to move a short distance a short length of tape will be fed forward or if allowed to travel all or nearly all of its limit of movement it will feed a longer length of tape. 30 When the handle is released and slips back into position, the clutches of course, prevent the feed and moistening rolls from moving backward but this return movement cuts the tape off between the feeding and the moistening rolls. 35

In the form shown I show a fixed blade 49 which is fastened across the machine to the side plates thereof as will be seen from Figure 6 and the movable blade 50 cooperates therewith to shear off the paper, the blade 50 being pivoted as at 51 and having on its free end the stout wire or similar connection 52 secured to the end of the bell crank 53 which is normally pressed upward 45 by the spring 54.

The tooth 55 is loose on its pivot and when the finger 56 and the plate 33 swing forward it lifts this tooth 55 and the knife is not disturbed. On the return movement however, the tooth 55 abuts against a projection or stud 57 on the short arm of the bell crank 53 which pulls down on the wire 52 and causes the blade 50 to be sharply brought down to shear off the tape. 50

The fingers 56 and the tooth 55 are close together so that even if a short length of tape is fed forward the parts are in position for cutting off the tape on the return movement. The parts are so disposed that 60 when the cutting is completed the finger 56 rides off the end of the tooth 55.

The tank 27 is removable so that it can be easily refilled or cleaned, having at its rear end the socket 58 which has at the front 65 an upwardly extended splash plate 59 to

prevent water from being splashed up against the tape before it is cut and is supported at its front end by the front plate 60 supported on one or more feet 61 which fit over the cross bar 62.

Suitable spring fingers 63 are installed to prevent the paper from sliding around on the moistening roll. To prevent the paper from curling out of its path of travel I arrange a plate 64 with its slightly inclined end 65 which holds the tape in alignment between the feeding roll and the knife and the plate 66 with the inclined edge 67 between the knife and the moistening roll. This plate 66 is also disposed so that it acts as a guard or bearing for the knife when it is moving upward, these plates being secured to a cover 68 pivoted at the back at 69 so that when the cover is raised these plates go with it and there is ready access to the cutting device and the feeding and moistening mechanism and new tape can be easily started through the machine when the cover is off.

I arrange a loose roller 70 which rides freely between the plate 59 and the moistening roll 26 and acts to shed excess water from the moistening roll so that nothing except the thin film necessary to thoroughly wet the gummed side of the tape, is carried over by the roller.

In operating the machine after proper adjustment for the length of tape desired has been made, the handle is pressed down which through the rack, the gears, and the clutches operates all the rolls and they feed the required amount of tape when the fingers release the handle and the handle snaps back and as it approaches the end of its return movement it has sufficient momentum to snap the movable blade down and the tape is severed with its end projecting out of the front of the machine.

To withdraw the rest of the severed part and to moisten it in its withdrawal, the paper is grasped and pulled and the moistening rolls are thus freely rotated since the clutch of the moistening rolls is released and there is no movement of the gears or any of their associated parts. It will be noted, however, that they are kept in positive contact so that when the machine is again started there is no lost motion and the feeding of the paper is initiated as soon as the handle of the rack is pressed down.

I claim:

1. A tape feeding machine comprising a frame to hold a roll of tape, an arc-shaped rack pivoted to the frame, a pair of gears each gear being in direct and constant mesh with the rack, sets of rollers to be driven by the gears, and a clutch connection between each gear and its set of rollers whereby each set of rollers can be rotated forwardly independent of its gear.

2. A tape feeding machine comprising a frame to hold a roll of tape, an arc-shaped rack having a handle thereon the rack being pivoted so that it can be swung, a set of feed rollers, a set of moistening rollers, a gear on each set of rollers said gears being in constant mesh with the rack, a knife, means for operating the knife from the rack on its return movement, a spring to cause such return movement, and a clutch connection between the set of moistening rollers and its gear so that the said rollers can be rotated forwardly to release the severed tape while the gear thereof and the actuating mechanism thereof is yieldingly held against movement by the spring.
3. A tape feeding machine comprising a frame for holding tape, a feeding mechanism, a moistening mechanism, means for operating said mechanisms, a cutting device with a vertically movable knife between the feeding mechanism and the moistening mechanism, a cover for the frame, said cover including plates to prevent tape from curling out of its path of travel between said mechanisms and the knife.
4. A tape feeding machine comprising a frame for holding tape, a feeding mechanism, a moistening mechanism, means for operating said mechanisms, a cutting device with a vertically movable knife between the feeding mechanism and the moistening mechanism, a cover for the frame, said cover including plates to prevent tape from curling out of its path of travel between said mechanisms and the knife, the knife bearing against one of said plates when it is elevated out of its cutting position.
5. A tape feeding machine comprising a frame having a well at one end for holding a roll of tape the frame having side plates at one end with bearings therein, feeding rolls mounted in the bearings, moistening rolls mounted in other of said bearings, a cutting device comprising a stationary blade and a movable blade above it to co-operate therewith in severing the tape, a gear and clutch on one of the feeding rolls, a gear and clutch on one of the moistening rolls, a pivoted arcuate rack in mesh with the gears and having a handle projecting therefrom, a shield covering the rack and clutches and having a slot to receive the shank of the handle, a stud on the rack and an adjustable stop on the shield to limit the swinging movement of the rack.
6. A tape feeding machine comprising a frame having a well at one end for holding a roll of tape the frame having side plates at one end with bearings therein, feeding rolls mounted in the bearings, moistening rolls mounted in other of said bearings, a cutting device comprising a stationary blade and a movable blade above it to co-operate therewith in severing the tape, a gear and clutch on one of the feeding rolls, a gear and clutch on one of the moistening rolls, a pivoted arcuate rack in mesh with the gears and having a handle projecting therefrom, a shield covering the rack and clutches and having a slot to receive the shank of the handle, a stud on the rack and an adjustable stop on the shield to limit the swinging movement of the rack.
- In testimony that I claim the foregoing, I have hereto set my hand, this 22nd day of March, 1924.
- CHARLES G. MORTIMER.
